UNITED STATES PATENT OFFICE.

GEORGE F. MANSFIELD, OF PASCAGOULA, MISSISSIPPI, ASSIGNOR OF ONE-HALF TO
FRANK H. LEWIS, OF PASCAGOULA, MISSISSIPPI.

CLOTH-MEASURING MACHINE.

1,238,798.

Specification of Letters Patent.

Patented Sept. 4, 1917.

Application filed February 18, 1916. Serial No. 79,151.

To all whom it may concern:

Be it known that I, GEORGE F. MANSFIELD, a citizen of the United States, residing at Pascagoula, in the county of Jackson and State of Mississippi, have invented a new and useful Cloth-Measuring Machine, of which the following is a specification.

This invention relates to an improved machine for measuring cloth directly from the bolt, and has for an object to provide a machine of this nature, which is relatively compact, and which may be erected or mounted in a relatively small space, so as to be used in department stores, and other cloth handling places, where it is desired to take inventory of stock, or to measure off cloth to ascertain the exact quantity thereof, or to sever the cloth into desired lengths.

Another object of this invention is to provide the above outlined mechanism which means for cutting the cloth in predetermined lengths, or to provide the machine with a cutter mechanism which is caused to actuate upon the measuring off of a certain predetermined length of cloth. The invention contemplates, in conjunction with this object of the invention, means for arresting the movement of the cloth through the device, during the cutting action and to transmit the motion of the cloth operating means to the cutter, so as to actuate the cutter transversely of the cloth to sever the same.

The invention further aims at the provision of an improved means for clamping the cloth and holding it taut at that portion which is to be severed by the cutting mechanism, so that the cutting knife may operate freely and without undue resistance in its transverse movement.

A still further object of the invention is to provide cutting mechanism which is so associated with the measuring or counting mechanism that the counting mechanism may be adjusted to various lengths in yards, or various fractions thereof, such as quarter yards, so as to actuate the cutting mechanism after the passage of a predetermined desired length of the cloth has passed the cutter.

Besides all of the above noted objects and advantages of the invention, the present invention contemplates the provision of a relatively light tubular frame having an adjustable upright therein to support one side of the mechanism, and which is adjustable with respect to the sides of the frame to ac-

commodate cloth varying in width; to provide improved means for holding the original bolt of cloth from which the cloth is taken to be measured and cut; to provide an improved cutting mechanism which is automatic in its action, and which is automatically returned to its initial position for repeating its cutting operation when next tripped; to provide an improved counting or measuring mechanism for indicating to the operator just how many yards and fractions thereof of the cloth passes through the machine, and wherein the parts of the counting mechanism are relatively few and are so arranged and constructed that but relatively few moving parts are employed, and some of these parts only intermittently; to provide the machine with an improved means for setting the trip for the cutter, and combining with the trip a shiftable drive pulley or means which, when tripped, is adapted to actuate the cutting mechanism, and which normally operates the cloth carrying mechanism to move the cloth through the machine; and to provide an improved roll holder for the cloth which is positively driven to wind the cloth thereon.

Various other objects and advantages of this invention will be brought out in the following specific description of the present preferred embodiment of this invention, the same being illustrated in the accompanying drawings, wherein—

Figure 1 is a front elevation of the improved cloth measuring machine, the dotted lines at the upper right hand corner of the figure showing the manual means, which may be employed for actuating the machine.

Fig. 2 is a right side elevational view of the machine.

Fig. 3 is a central vertical section, taken from front to rear through the machine.

Fig. 4 is a transverse vertical sectional view, taken through the left hand side of the machine, showing the securing means for the adjustable upright in the machine.

Fig. 5 is a fragmentary enlarged sectional view, taken through the right hand side of the machine, and showing the operative parts thereof.

Fig. 6 is a fragmentary sectional view, taken through the operative parts, on the line 6—6 of Fig. 5, the plane of the section extending from front to rear of the machine.

Fig. 7 is a detail fragmentary sectional view

110

view, taken horizontally on the line 7—7 of Fig. 5, and looking downwardly on the cutter actuating gears.

Fig. 8 is an end view of the cloth support, showing the means for expanding the binding rods of the support.

Fig. 9 is a detail fragmentary view, enlarged, of the left hand end of the trip for returning the cutter to normal inactive position.

Fig. 10 is a front elevation of the machine, showing a modification of the structure thereof.

Fig. 11 is a detail enlarged edge view of the number wheel, showing the novel arrangement of the numbers thereon.

Referring to these drawings, wherein like parts are designated by similar numerals of reference, 10 designates a pair of blocks, 20 which constitute a base for the machine, and may be separate members as shown, or be given any other desired configuration, or assemblage, as is found convenient or desirable in the erection and use of the machine.

25 Socket plates 11 are seated upon the upper flat faces of the base members 10, and have upstanding sockets 12, in which are seated the lower ends of standards 13 and 14, which rise upwardly in parallelism and are held in spaced relation at their upper ends by a cross piece 15. The socket plates 11 are fixed in position upon the base members 10 by screws 16, or other desired fastening devices.

30 The standards 13 and 14 are preferably tubular as shown and the cross piece 15 is tubular, the standards and the cross piece being joined at their adjacent ends by elbows 17. The standards 13 and 14 are braced adjacent their upper and lower ends by the vertically spaced apart brace bars 18 and 19, located, respectively, in the upper and lower portions of the frame, and are used not only to brace the standards 13 and 45 14, but to also support certain of the herein-after described mechanism.

The frame is provided with a transversely adjustable upright 20. The upright is tubular and provided upon its upper and lower ends with preferably spherical heads 21 and 22, having transverse openings therein to snugly receive, through the heads 21 and 22, the adjacent ends of the braces 18 and 19. The braces 18 and 19 are connected to the 50 standards 13 and 14 by T couplings 23, which form a rigid connection between the standards and the braces, so as to firmly support the adjustable upright 20. As may be best seen from Fig. 4, the upright 20 is 55 tubular and is provided in its upper and lower ends with latches 24 reduced at their outer portions to provide stop shoulders 25, and adapted to project into the transverse openings through the heads 21 and 22 for 60 engagement with the teeth of racks 26, which 65

are formed upon the opposed respective upper and lower faces of the braces 18 and 19. The opposite ends of the upright 20 are threaded into sockets 27, formed in the inner opposite ends of the heads 21 and 22, 70 so as to hold the upright rigidly to the heads and provide at the inner ends of the sockets suitable shoulders to receive the shoulders 25 of the latches thereagainst. Springs 28 are placed in the opposite ends of the upright 20, and each has an end bearing against the adjacent latch 24, while the opposite end of each spring is held in compressed position against the adjacent latch by means of stops 29. The latches 24 are connected to wires, or relatively flexible rods 30, which extend toward an intermediate portion of the upright 20, as at a point spaced slightly above the middle portion of the upright, and are there connected to 80 blocks 31 slidable in the upright, and having outstanding thumb pieces 32, which project laterally through a slot 33 in one side of the upright 20. The springs 28 are adapted to force the latches outwardly into 85 contact with the racks 26, and to thus draw the blocks 31 apart and spread the thumb pieces 32. The latches 24 are retracted by compressing the thumb pieces 32 together, as is apparent. With this construction, the 90 upright 20 may be moved toward or from the standard 14, so as to vary the width of the passage through the frame to accommodate cloth varying in widths.

The lower end of the frame is adapted to 100 support a bolt of cloth, which is to be measured or cut. For this purpose, the standard 14 and the upright 20 are each provided with an inwardly extending spindle 34 mounted to slide transversely through a 105 four-way coupling 35 interposed in the standard 14 and also in the upright 20. The spindles 34 are adapted to move toward and from each other, and carry upon their inner ends a pair of opposed disks or wheels 36, 110 each having at its inner face a diametrically extending grooved projection 37 to receive the adjacent end of a board 38 upon which the bolt of cloth is rolled. Springs 39 surround the spindles 34, and bear at their 115 inner ends against the hub portions of said wheels 36, and bear at their outer ends against the inner sides of the couplings 35 to thus urge the spindles 34 inwardly, and 120 yieldingly hold the projections 37 against the opposite ends of the board 38 of the bolt of cloth. These springs 39, and the slidable mounting of the spindles 34, provide means for adjusting the disks 36 to various distances apart to accommodate cloth varying 125 in width.

The cloth 40 is carried from the bolt 41 over a support and upwardly through the frame. This support comprises a pair of inwardly extending brackets 42 and 43, lo- 130

cated respectively upon the standards 13 and 14, the brackets being of substantially U-shape form, as shown, and projecting considerably into the space between the standards. The bracket 43 is of less size than the bracket 42, so as to dispose the major portion of the support in line with the cloth 40, which is carried intermediate the upright 20 and the standard 14. Each bracket, 10 42 and 43, has at its inner end a relatively straight cross bar 44, which, as best shown in Fig. 8, has near its opposite ends elongated slots 45 to receive the adjacent ends of outer tubes or rods 46, which extend 15 across the frame, and are adapted to bear against the outer side or face of the strip of cloth 40. See Fig. 3. The inner rods or tubes 47 of the support comprise relatively stationary members extending between the 20 brackets 42 and 43, and being spaced inwardly to slight extent from the outer rods 46. The inner rods 47 are mounted rigidly in the bars 44 of the brackets and are held in parallelism throughout their lengths. The 25 outer bars 46 are provided upon their extremities with pins 48, upon each of which is hinged one end of a link 49, each pair of links being pivotally connected at their free ends to provide a toggle joint connecting the 30 outer rods 46. The pins 48 are also connected together by contracting springs 50 adapted to normally urge the outer bars 46 inwardly against the inner bars 47. The inner bars 47 are adapted to lie against the 35 inner side or face of the strip of cloth 40, and when the outer bars 46 are contracted, by means of the springs 50, they bind the cloth tight against and over the inner rods 47 to hold the cloth taut over the rods. It 40 is, of course, understood that any number of these rods or tubes 46 and 47 may be employed in order to tension the cloth properly, as it passes upwardly through the frame. As shown in Fig. 1, the upright 20 45 is provided with a second coupling 51 through which is slidably mounted a spindle 52. The spindle 52 has mounted rotatably upon its inner end, a disk or wheel 53, provided with a relatively long diametrically 50 extending grooved projection 54 to receive one end of a relatively flat frame 55. The frame 55 comprises two sections, the main section, and a second telescoping section 56. Both sections are of U-shape, the section 55 55 being of larger diameter and adapted to receive therein the ends of the section 56, whereby the frame, designated as a whole as 55, may be extended or contracted to accommodate cloth varying in width, and consequently different distances between the disk 53, and a second disk or wheel 57, arranged in the opposite side of the frame.

With reference to Figs. 1 and 5, of the drawings, it will be noted that the upper 55 disk or wheel 57, at the right hand side of

the machine is provided with an inwardly extending projection 58 receiving the adjacent end of the swinging frame 55, which latter may be pivoted at its ends as shown. The wheel 57 is provided with a hub 59 having a concaved outer face concentric about a shaft 60, which is journaled in a coupling 61 carried by the standard 14, directly opposite to the hub 59. The shaft 60 is adapted to turn freely in the wheel 57, and has 70 keyed thereon a drive pulley 62 peripherally grooved, as at 63 to receive a belt, or the like, from a suitable driving element, such as an electric motor. Freely mounted upon the shaft 60, and at the outer side of the pulley 80 62, is a second pulley 64, provided with a concaved hub 65, which faces toward the hub 59. The pulley 62 is slidable longitudinally on the shaft 60, but is rotatable therewith. The pulley 62 has upon its opposite sides convexed hub portions 66 and 67 adapted to fit into the concavities of the hubs 59 and 65, and to provide therewith clutches to alternately connect the drive pulley 62 with the wheel 57, and the pulley 64. The 90 outer extremity of the shaft 60 is provided with an angular projection or shank 68 to which may be fitted a handle 69 in the form of a crank, as shown in dotted lines in Fig. 1. Thus, the improved machine may be operated either manually, or by means of a suitable driving element.

The drive pulley 62 is provided with a shifting lever 70 (Fig. 5), in the form of a relatively flat plate arranged vertically, and 100 adapted to slide in a horizontal direction upon a pair of vertically spaced apart pins 71 and to be normally urged outwardly thereon by a pair of compression springs 72 encircling the pins, and secured at their 105 outer ends to the standard 14 and at their inner ends to the adjacent outer face of the shifting lever 70. The pins 71 are supported by the standard 14 and preferably extend diametrically therethrough, and are 110 threaded at their outer ends, as shown in Fig. 5, to engage through correspondingly threaded openings formed in the outer side of the standard. This provides for a rigid structure, which holds the pins 71 from vibration in any direction. A handle 73 projects, outwardly from an intermediate portion of the plate of the lever 70, through the standard 14, and is turned upwardly at right angles for grasping by the hand when it is 115 desired to push the handle in against the tension of the springs 72, and thus shift the drive pulley 62 into interlocking engagement with the wheel 57 to drive the same and wind up the cloth. The shank 74 of the 120 shifting lever 70 is provided in its outer edge with a notch 75 to receive the end of a latch 76 urged toward the notch by a spring 76a, Fig. 6 hinged upon a pin 77, carried by the standard 14, and having its lower end in 125 130

contact with a toothed wheel 78, which, when rotated, is adapted to rock the latch 76, and raise the end thereof out of the notch 75 in the side of the shank 74. This operation of the latch 76 releases the shifting lever, whereby the same is adapted to spring outwardly under the tension of the springs 72, which contract and move the pulley 62 against the free pulley 64. The shifting lever 70 is provided with fork arms 79 engaging against the opposite sides of the pulley 62, so as to shift the same in opposite directions when the shifting lever 70 is moved outwardly by the springs 72, and when the shifting lever 70 is forced inwardly by the handle 73. The toothed wheel 78 is provided with an elongated hub or sleeve portion 80, which projects outwardly through the standard 14, and has bearing support therein. The outer end of the sleeve terminates short of the end of a shaft 81, which passes entirely through the sleeve 80 and the toothed wheel 78, and serves as a shoulder to receive thereagainst a hub 82, which carries a combined indicating and tripping arm 83. The arm 83 is adapted to turn with the shaft 81, and to traverse the face of a dial 84, which is mounted on the outer end of the sleeve 81, but is held from rotation therewith by a support 85, or the like. The sleeve 80 carries a trigger 86 having a sleeved hub fitting over the sleeve 80, and being secured thereto by means of a set screw 87. The trigger 86 is provided with an adjustable finger 88 upon its outer end adapted to be swung into the path of the indicator and tripping arm 83, as shown in full lines in Fig. 5, or to be swung upwardly out of the path thereof, as shown in dotted lines in Fig. 5. The movement of the trigger 86 turns the sleeve 80 and the toothed wheel 78 to trip the latch 76, release the shifting lever 70, and move the drive pulley 62 into interlocking contact with the loose pulley 64, as shown in Fig. 1.

The inner end of the shaft 81 projects beyond the toothed wheel 78, and has mounted thereon an indicating or number wheel 89, provided upon its inner face with a plurality of equi-distantly spaced apart pins or projections 90, representing the number of advancements which are necessary to make a complete revolution of the number wheel. As may be best seen from Fig. 11 this number wheel 89 has its periphery divided longitudinally into two parts, each part being preferably divided up into fifty equal spaces. One side or part of the wheel bears numbers consecutively arranged from 1 to 50, while the opposite side of the wheel 89 has consecutively arranged in the spaces thereof, numbers from 51 to 100. These numbers are so arranged upon the periphery of the wheel 89, that when the number 50 is on one side 65 of the wheel, at the next advancement of the

wheel, the number 51 may be read at the opposite side, so that by this peculiar arrangement, the wheel 89 is made to indicate 100 steps, or marks of a predetermined value, by two consecutive revolutions of the 70 wheel. From Figs. 1 and 5, it will be seen that a small plate 91 is mounted inwardly of the number wheel 89 and supported upon bracket arms 92, so as to lie flat against the rear face of the web of cloth 40, as it passes 75 upwardly from the lower bolt 41. A post 93 projects inwardly and overhangs, or is spaced forwardly from the plate 91, and has hingedly mounted upon its outer end, a bearing bracket 94, which, by means of one or 80 more springs 95, is urged rearwardly toward the plate 91.

A shaft 96 is journaled in the bearing bracket 94, and has on one end a contact wheel 97, adapted to roll over the web 40 as 85 it passes upwardly through the frame, and for this purpose is preferably provided with a rubber, or other frictional, peripheral surface. The inner end of the shaft 96 carries a striker wheel 98 provided upon its outer 90 side with a projecting stud 99, the path of movement of which intersects the path of movement of the pins 90, so that upon each complete revolution of the stud 99, the same strikes a pin 90, and advances the number 95 wheel 89 one step. Preferably, the wheels 97 and 98 are of the same diameter, so that upon one complete revolution of the wheel 97, the wheel 98 receives a complete turn, and the wheel 97 is preferably given such 100 diameter that each complete turn is effected by the passage of one quarter of a yard of the web 40 therebeneath to thus indicate upon the number wheel 89, at each advancement thereof, that a quarter of a yard of 105 the cloth, or other material, has passed upwardly beneath the contact wheel 97.

The present machine is also provided with means for cutting the cloth in desired lengths, and for this purpose provides a 110 cutting mechanism, which is automatically tripped or actuated after the passage of a predetermined length of the web 40 upwardly through the machine. The support over which the cloth passes is used for this 115 purpose, and the intermediate bars 47 are provided with a carriage or traveler 100, Fig. 1, which preferably comprises a pair of sleeves, one for each of the tubes or rods 47, joined by a web 101, from the intermediate 120 portion of which a knife or cutter 102, Fig. 7, extends outwardly and is preferably inclined upwardly toward the bracket 42 at a slight angle. The web 101 is located beneath the plane of the web 40 as it passes 125 over the intermediate rods 47, and the cutter or knife 102 projects considerably, above, or outwardly from, the web 40. The carriage 100 is slidably on the support, and adapted for movement transversely across the ma- 130

chine from the bracket 43 to the bracket 42. To effect this operation, the carriage 100 has connected to the inner side thereof, one end of a flexible cord or cable 103, which passes 5 transversely beneath the support and over a pulley 104, and is thence carried back to the opposite side of the frame, where it is wound, upon a spool or drum 105.

As may be best seen from Fig. 5, the drum 105 has end flanges 106 and 107, the latter being provided with peripheral teeth 108, adapted to mesh with the laterally extending teeth 109 of a pulley 110. The pulley 110 has an outwardly extending stem 111 passing through the standard 14, and having bearing therein to support the pulley 110. The stem 111 also passes through the base of the bracket 43, so as to mount the pulley within the bracket and opposite to 15 the drum 105. The drum 105 is keyed upon a vertical spindle 112, which is mounted for rotation in the opposite arms of the bracket 43. The spindle 112 has arranged thereabout a coiled spring 113, secured at one 20 end to the arm 114 of the bracket 43, and at its opposite end as at 115, to the spindle. This spring 113 is adapted to be compressed when the spindle 112 is turned in one direction, and when the spindle is released, is 25 adapted to rotate the spindle in the opposite direction. The cable 103, which passes over the drum 105 is given a sufficient number of turns or laps over the drum to frictionally connect the cable to the drum, the 30 end of the cable being then carried to the carriage 100, and secured to the outer side thereof. The drum 105 is provided with a peripherally grooved hub 116 projecting downwardly therefrom, and with which is 35 engaged one arm of a bell crank lever 117, which is pivoted as at 118 in the bracket, and has its downwardly extending arm hingedly connected to a finger 119, projecting downwardly from a transverse bar 120, 40 passing through the lower tube 47 of the support. This bar 120 is provided upon its opposite ends with shifting fingers 121 and 122, adapted for contact with the carriage 100, as the latter is reciprocated back and 45 forth in the support to slide the bar 120 first toward one side of the frame, and then toward the opposite side thereof. This shifting of the bar 120 swings the bell crank lever 117 to shift the drum 105 on the 50 spindle 112 and move the teeth 108 of the drum into and out of engagement with the teeth 109 of the pulley 110. Thus, the drum 105 is connected and disconnected with respect to the pulley 110 by the shifting of the 55 bar 120. The pulley 110 is driven by the rotation of the upper pulley 64 through a belt 123, which passes over the pulley to communicate motion therebetween.

Before the cloth is fed upwardly through 60 the machine, and it is desired to cut off a

definite length, the trigger 86 is set, so that the tripping arm 83 may strike the finger 88 of the same at the desired measurement, and release the shifting lever 70, so that the same may move outwardly into the position 70 shown in Fig. 1, and thus connect the drive pulley 62 to the loose pulley 64. The motor, or other means for turning the shaft 60 now drives the cutting mechanism, to turn the gear 110, the drum 105, and operate the 75 cable 103, to move the carriage 100 transversely across the machine from the bracket 43 to the bracket 42. During this operation of the cutting mechanism, it is necessary to hold the cloth taut over the inner rods or 80 tubes 47, and to accomplish this purpose the springs 50 are employed to draw the outer rods 46 toward each other and bind the web between the same and the rods 47. The springs 50 are normally held stretched or 85 under tension by the links 49, Fig. 8, to release the web 40 when the latter is traveling over the support. The standard 14 carries a bell crank lever 124 (Fig 5), pivoted at 125, and having its vertical arm connected 90 to the fork 79, of the shifting lever 70, so that when the latter is moved inwardly to drive the upper reel, the bell crank lever 24 will be tilted upwardly as shown in Fig. 5, to spread the rods 46 and release the cloth. 95 The horizontal arm of the bell crank lever has connected thereto a flexible cable 126, which passes downwardly through the frame over pulleys 127 and 127^a, and thence is connected at 128 to the hinged inner ends of 100 the links 49, as shown in Fig 8. Thus, tension placed on the cable 126 moves the toggle links 49 inwardly and spreads the springs 50 and the outer rods 46. The links 49 on the left hand side of the frame are 105 spread by a cable 129, which passes upwardly over a pulley 127, and across the frame, and connects to the cable 129 adjacent the bell crank lever 124.

In Fig. 10 of the drawings, there is shown 110 a modified form of the machine above described, and which embodies the features of the present invention. In this modified structure, the parts are of the identical form and arrangement of the preferred form of 115 the invention, with the exception of the following modifications.

The support which passes across the frame between the standards 13 and 14 is made up of a pair of brackets 130 and 131 of U-shape, 120 and which project inwardly toward one another. The bracket 131 is the longer or larger bracket, and thus offsets the support toward the right hand side of the frame, so as to dispose the support substantially in 125 alignment with the web 40, which passes upwardly through the frame. These brackets 130 and 131 have inner opposite cross bars, which are relatively straight, and which support the opposite ends of transversely 130

extending and spaced apart rods 132 and 133. The rod 133 is the intermediate rod of the assemblage, shown in this Fig. 10, and is adapted to receive over its forward face the web 40. The rods 132 are the outer rods, and are spaced above and below the intermediate rod 133, and are adapted to bear against the outer face of the web in order to distort the same from its plane of travel and tension the web over the intermediate rod 133. It is thus seen that in the modified form the support is made up of a number of stationary rods spaced apart and engaging against the opposite sides of the web, so as to offset the same from its line of travel and thus properly tension and smooth the cloth, as it is fed upwardly through the device. The number wheel 89 is mounted on the outer end of a stud or short shaft 134 mounted in a suitable bearing 135 projecting inwardly from the standard 14, so as to hold the number wheel 89 in the position shown, and for contact with the striking stud or projection 99, as in the preferred form.

The modified form of the machine is adapted to measure cloth only, and is not provided with a cutting mechanism. By eliminating this mechanism, the drive pulley 136 is fixed to the drive shaft 137 to which is also fixed the wheel 138. The wheel 138 is provided with the diametrically extending projection 139, which is grooved in the manner above described to receive therein the upper winding frame 55. The shaft 137 has the squared shank 68, as in the preferred form, whereby the shank may be turned manually. In all other respects this modified form of the invention is similar to that above disclosed, the changes made, being simply to eliminate the cutting mechanism, as for certain uses the cutting mechanism is not desirable, and a machine according to the modified structure provides an economical and practical machine for measuring the cloth.

The operation of this modified form of the machine, as above set forth is substantially identical with the preferred form as the latter differs only in the addition of the cutting mechanism, the automatic means for tripping the same, and the means for interrupting the movement of the cloth.

When it is desired to ascertain the length of cloth and to cut the same, the web 40 is fed upwardly through the support by passing the web first outwardly between the lower bars 46 and 47, and then rearwardly between the upper bars 46 and 47. This disposes a length of the cloth in flat condition across the intermediate bars 47. The web is carried over the plate 91 and beneath the contact roller 97, and is then secured to the frame 55 by engagement with the pins 140. The shaft 60 is turned in any suitable man-

ner, such as by driving the pulley 62, or turning the handle 69. The handle 73 is forced inwardly toward the standard 14 to shift the lever 70 inwardly upon the pins 71 and cause the arms 79 of the lever to slide the pulley 60 toward the wheel 57. This action causes the clutch faces 59 and 66 to engage, whereby the wheel 57 is turned to rotate the frame 55 and wind the cloth upon the upper frame. As the web of cloth 40 moves upwardly through the frame, its frictional contact rotates the wheel 97, whereby the shaft 96 is turned to rotate the wheel 98 and the striker 99. Upon each revolution of the striker 99, the same engages a pin 90 of the number wheel 98, to thus advance the same one step. Each advancement of the wheel moves the numbers so that an additional predetermined length of the cloth is passed upwardly through the frame. The intermittent rotation of the number wheel 89 is transmitted through the shaft 81 to the indicating and tripping arm 83. The arm 83 is intermittently rotated in front of the dial 84, which dial may be provided with any suitable numbering or indications desired. If it is desired to cut the cloth at a certain length, the finger 88 of the trigger 86 is swung down into the path of the arm 83, and the trigger itself is turned about the dial until it reaches the desired indicated length, marked on the dial, when it is frictionally held in such position. The latch 76 is engaged in the notch 75 of the shifting lever, and also in the throat between two of the adjacent teeth of the wheel 78, whereby the latch is held in the notch, and in position ready to be released therefrom, upon the rotation of the wheel 78. The inward movement of the shifting lever 70 draws the cables 126 taut, so as to operate the toggle links 49 and spread the outer bars 46 away from the inner bars. The latch 76 which holds the shifting lever in its innermost position also serves to hold the cables 126 taut and thus hold the support in position to admit of the relatively free movement of the web upwardly therethrough. After the arm 83 has turned through a predetermined distance, and comes in contact with the finger 88 of the trigger, the latter is advanced with the arm 83 upon the next advancement of the number wheel, so that the trigger is actuated, the wheel 78 is advanced one tooth, and the latch 76 is lifted out of the notch 75 to release the shifting lever 70. This releasing of the shifting lever admits the outward movement thereof under the tension of the springs 72. The shifting lever thus disengages the pulley 62 from the wheel 57 and thereby arrests the upward feeding of the cloth through the frame. The pulley 62 is also drawn outwardly whereby the clutch members 65 and 67 of the pulley 62 and the pulley 64 are interlocked. Simultaneously

with the disengagement of the drive pulley 62 with the wheel 57, the cables 126 are released or slackened, whereby the springs 50 contract and the outer rods 46 are drawn toward the inner rods and clamp the web rigidly in the support and draw the same taut over the rods 47. As the pulley 64 is rotated, the belt 123 drives the lower pulley 110, and through the teeth 109 and 108 respectively, 10 drives the drum 105. The drum turns in such direction that the flexible cord or cable 103 moves the carriage 100 transversely of the frame from the bracket 43 to the bracket 42. This action of the carriage 100 draws 15 the cutter or knife 102 transversely through the flattened and taut portion of the web 40 to thus sever the same at a point between the inner rods or tubes 47. As soon as the carriage 100 reaches the bracket 42, it is 20 brought into contact with the shifting finger 122, and effects the sliding of the bar 120 through the lower tube 47. This sliding or shifting of the bar 120 rocks the bell crank lever 117 about its pivot 118 to move the 25 horizontal arm of the bell crank lever upwardly and thus shift the drum 105 out of alignment with the gear pulley 110. Thus the teeth 108 and 109 are drawn out of mesh and the drum 105 is free to turn in the opposite 30 direction under the tension of the spring 113. The spring 113 is wound or placed under tension by the action of the pulley 110, when it drives the drum to move the carriage 100 in the act of cutting the 35 cloth. The spring 113 now rotates the drum in an opposite direction and thereby returns the carriage 100 to the right hand end of the machine against the bracket 43. When the carriage 100 is returned to the bracket 43, 40 the carriage strikes the shifting finger 121 and shifts the bar 120 back into its normal position to thus swing the bell crank lever 117 in the direction to lower its horizontal arm, and thus move the drum 105 back into 45 alignment with the gear pulley 110. The cutting mechanism is now in position to be again actuated after the cloth is wound to another desired length upon the frame 55.

It is within the spirit of this invention to 50 make such other various modifications and changes of these specifically described and illustrated forms of this invention, as the scope of the following claims will permit, to adapt the machine to the conditions of use 55 and manufacture met with in the production and application of the invention.

What is claimed is:—

1. A machine as specified provided with a frame having upper and lower transverse braces, an upright in one side of the frame engaging the braces to guide the upright in its transverse adjustment in the frame, a latch in each end of the upright for interlocking engagement with said braces to hold the upright from movement when adjusted, 60 and means carried by the upright to be engaged by the hand to retract the latches and permit adjustment of the upright.
2. A machine as specified provided with a frame having upper and lower transverse braces provided with rack teeth, an upright in the frame at one side thereof having heads upon its opposite ends for engagement about said braces to guide the upright in its transverse adjustment in the frame, a latch in each end of the upright for interlocking engagement with said racks to hold the upright from movement when adjusted, and a pair of thumb levers projecting laterally from the upright, and having connection with said latches to retract the same and permit of the adjustment of the upright. 70
3. In a machine as specified, a frame, a bolt support in the lower end of the frame, a reel in the top of the frame adapted to receive the cloth from the bolt, operating means normally engaging the reel to turn it and rewind the bolt, a measuring device between the bolt support and the reel adapted to engage with the cloth to measure it, a cutting device between the bolt support and the reel, and shiftable means between the operating means and the cutting device and having connection with the measuring means whereby upon the rewinding of a predetermined length of the cloth the shifting means is adapted to shift the operating means from the reel to the cutting mechanism and cause the latter to sever the cloth. 80
4. In a machine as specified, a frame, a bolt support in the frame, a reel in the frame adapted to receive cloth from the bolt to rewind the cloth, operating means for engagement with the reel to turn the latter, a pair of bars fixed in the frame and extending across one side of the cloth, a second pair of bars adjustably mounted in the frame against the opposite side of the cloth and adapted for movement toward and from the fixed bars to clamp the cloth thereagainst, 90 cutting mechanism mounted on the fixed bars for severing the cloth when stretched thereover, and shifting means connected to the operating means and having connection with said second bars and with said cutting mechanism to clamp the cloth between the pairs of bars and sever the cloth between the fixed bars. 100
5. In a machine as specified, a pair of standards, a cross piece joining the upper ends of the standards, vertically spaced apart brace bars joining the standards and having racks upon their inner opposite faces, an upright slidably connected at its opposite ends to said braces and adapted for movement transversely in the frame, latches in the ends of the upright for engagement with said racks to lock the upright in adjusted position, springs in the opposite ends of the upright to normally urge the latches 110
6. In a machine as specified, a pair of standards, a cross piece joining the upper ends of the standards, vertically spaced apart brace bars joining the standards and having racks upon their inner opposite faces, an upright slidably connected at its opposite ends to said braces and adapted for movement transversely in the frame, latches in the ends of the upright for engagement with said racks to lock the upright in adjusted position, springs in the opposite ends of the upright to normally urge the latches 120
7. In a machine as specified, a pair of standards, a cross piece joining the upper ends of the standards, vertically spaced apart brace bars joining the standards and having racks upon their inner opposite faces, an upright slidably connected at its opposite ends to said braces and adapted for movement transversely in the frame, latches in the ends of the upright for engagement with said racks to lock the upright in adjusted position, springs in the opposite ends of the upright to normally urge the latches 125
8. In a machine as specified, a pair of standards, a cross piece joining the upper ends of the standards, vertically spaced apart brace bars joining the standards and having racks upon their inner opposite faces, an upright slidably connected at its opposite ends to said braces and adapted for movement transversely in the frame, latches in the ends of the upright for engagement with said racks to lock the upright in adjusted position, springs in the opposite ends of the upright to normally urge the latches 130

- against said racks, rods extending inwardly from the latches, blocks slidably mounted in the upright at an intermediate portion thereof and having connection with said rods, 5 thumb latches carried by the blocks and projecting laterally from the upright for engagement with the fingers to draw the blocks together and retract said latches, upper and lower spindles carried in one of said stands, and opposed upper and lower spindles carried in said adjustable upright, said spindles being adapted to support a bolt of cloth, said upright being adjustable to admit cloth of different widths in the frame.
- 10 6. In a machine as specified, a frame, a bolt support in the frame, winding mechanism in the frame for engagement with the cloth of the bolt to rewind it, a pair of spaced apart bars fixed in the frame and adapted to engage against one side of the cloth between the bolt support and the winding mechanism, a pair of movable bars arranged against the opposite side of the cloth and adapted for adjustment toward 15 the fixed bars to bind the cloth thereover, a knife slidably mounted on the fixed bars and projecting therebetween for severing the cloth, means for reciprocating the knife, operating means detachably connected to 20 the winding mechanism, and to the knife and the movable bars, whereby upon the adjustment of the operating means to stop the winding mechanism, said adjustable bars are moved against the cloth to bind the same 25 over the fixed bars and said knife is actuated to sever the cloth between the fixed bars.
7. In a machine as specified, a frame, a bolt support in the frame, winding mechanism 30 in the frame for receiving cloth from the bolt, a shiftable operating member adapted for movement toward and from the winding mechanism to operate and release the latter, a lever for shifting said operating member, means for locking the lever in 35 position for actuating the winding mechanism, a clamping device engaging the cloth between the bolt support and the winding mechanism and having connection with said 40 shifting lever to release the cloth when said lever is locked, a cutter in the frame to sever the cloth when clamped, and a measuring device in the frame to engage the cloth and having a tripping arm for engagement with said locking means, to release the lever upon the passage of a predetermined length of cloth from the bolt and clamp and cut the cloth.
8. In a machine as specified, a frame, bolt 45 supporting means in the opposite portions of the frame, a plate between said bolt supporting means over which the web of cloth from the bolt is adapted to pass, a contact wheel bearing against the web of cloth 50 to press the same against said plate and

rotate said wheel by the movement of the cloth in the frame, a second wheel spaced outwardly from the path of the web, a projection carried by the second wheel, and a number wheel mounted on the frame adjacent the second wheel, and having a plurality of pins projecting therefrom and equidistantly spaced upon the wheel for contact consecutively with said projection to advance the number wheel upon each 75 complete revolution of the contact wheel.

9. In a machine as specified, means for supporting and conveying a web of cloth, a plate for engagement against one side of the web, a spring pressed bracket at the 80 opposite side of the web, a shaft carried by the bracket, a friction wheel fixed to one end of the shaft opposite the plate and adapted to press the web against said plate and turn the contact wheel by the movement of the web, a second wheel carried upon the opposite end of said shaft, a projection mounted on the second wheel, a number wheel arranged adjacent the web, and a plurality of equi-distantly spaced pins 85 carried by the number wheel and adapted for consecutive engagement with said projection, to intermittently advance the number wheel upon the turning of the contact wheel.

10. In a machine as specified, a frame, a bolt support in the bottom of the frame, winding means in the upper end of the frame, a counter arranged intermediate the frame to be actuated by the passage of a 100 web of cloth upwardly from the bolt to the winding means, cloth cutting mechanism at the intermediate portion of the frame, and operating mechanism for the cutting mechanism controlled by said counter.

11. In a machine as specified, a frame, means for conveying a web of cloth upwardly through the frame, a measuring device in the frame, a cutting device in the frame, and means controlled by the measuring device for effecting the operation of said cutting device upon the passage of a predetermined length of the web upwardly through the frame.

12. In a machine as specified, a frame, 115 means for feeding a web upwardly through the frame, cutting means, and controlling devices between the cutting means and the web feeding means to trip the cutting means upon the passage of a predetermined length 120 of the web upwardly through the frame.

13. In a machine as specified, a frame, a bolt support in one end of the frame, a frame support in the opposite end of the frame adapted to receive the free end of the bolt 125 of cloth, a drive pulley, a shifting lever for normally holding the pulley against said frame support to rotate the latter and wind the cloth on said second frame, measuring means in the frame for contact with the web, 130

a trigger connected to said shifting lever for operating the same upon the registration on the measuring device of the passage of a predetermined length of the web through 5 the frame, and disconnecting the drive pulley from the frame support, and cutting means in the frame for connection with said lever, whereby the cutting means may be operated upon the shifting of the lever and 10 when the feeding of the web upwardly through the frame is stopped.

14. In a machine as specified, a bolt support, winding mechanism adapted to receive cloth from the bolt, a clamp engaging the 15 cloth between the bolt and the winding mechanism, a cutter mounted on the clamp and adapted to sever the cloth when clamped, an operating member shiftable between the winding mechanism and the cutter 20 and clamp to alternately operate the same, a spring pressed lever engaging the operating member to hold it normally out of contact with the winding mechanism, an adjustable locking device to hold the lever in 25 contact with the winding mechanism for actuating the latter, and a measuring device engaging the cloth and having a tripping arm for engagement with said locking device to release it and free the lever, whereby 30 the latter is permitted to shift the operating member to release the winding mechanism and actuate the cutter and the clamp.

15. In a machine as specified and in combination, a frame, a bolt support in the 35 frame, winding mechanism in the frame spaced from the bolt support to receive the end of the bolt to rewind it, cloth measuring mechanism in the frame adapted for contact with the cloth to be rewound, cloth cutting mechanism in the frame between the bolt support and the winding mechanism and being normally at rest, operating mechanism in the frame adapted for connection with the winding mechanism to actuate it, and a 40 shiftable device connected to the operating mechanism and to the cutting mechanism to

hold the latter inoperative when the winding mechanism is actuated, and for shifting the operating mechanism into contact with the cutting mechanism, and for releasing the 50 winding mechanism.

16. In a machine as specified, a frame, a bolt support in the frame, a reel in the frame adapted to receive the web of cloth from the bolt, fixed bars extending transversely in the 55 frame at one side of said web, clamping bars arranged transversely in the frame against the opposite side of the web, springs connecting said clamping bars to urge the same against the fixed bars and bind the web 60 thereover, a carriage slideable on the fixed bars, a knife on the carriage projecting into the plane of the web, a spool carried in one side of the frame opposite the fixed bars, a cord on said spool having its opposite ends 65 connected to the opposite sides of the carriage and being looped across the frame, a pulley in the opposite side of the frame to receive the looped cord thereover, driving means for turning the spool to move the 70 carriage and knife in one direction across the frame, a spring engaging the spool to actuate the same and draw said carriage backwardly across the frame, an operating element between said reel and said driving 75 means and having connection with said clamping bars, said operating element being adapted to be shifted into contact with the reel to rewind the cloth and to spread the clamping bars to free the cloth, and being 80 adapted to be shifted into contact with said spool driving means to sever the cloth and to release the clamping bars for clamping the cloth while being cut.

In testimony that I claim the foregoing 85 as my own, I have hereto affixed my signature in the presence of two witnesses.

GEORGE F. MANSFIELD.
